KNITTED COAT OR SIMILAR ARTICLE

David M. Goodstein, New York, N. Y.

Application December 14, 1954, Serial No. 33,552

Term of patent 3½ years

(Cl. D3—4)

Fig. 1 is a front view of my design showing my new knitted coat or similar article, and

Fig. 2 is a rear view thereof.

I claim:

The ornamental design for a knitted coat or similar article, substantially as shown.
